UNITED STATES PATENT OFFICE.

DANIEL E. NORRIS, OF ROBINSON, ILLINOIS, ASSIGNOR TO NORRIS BROTHERS, INCORPORATED, OF ROBINSON, ILLINOIS, A CORPORATION OF ILLINOIS.

WORKING-BARREL-CLEANING DEVICE.

Application filed March 1, 1927. Serial No. 171,848.

In operating oil wells it is not unusual to withdraw the pump plunger for renewing the pump cups and also not unusual to withdraw the standing valve from the working barrel in order that the working parts of the valve may be renewed. To this end working barrels are usually provided with screws at the upper ends of their cages which may be engaged by a screw lowered into the well and 5 screwed into engagement. Working barrels often become coated with deposits from the material pumped and this is more pronounced adjacent to the standing valve. The object of the present invention is to assist in clearing the working barrel of such deposit and 10 provide a means by which the standing valve may be engaged with certainty and withdrawn from the working barrel. Features and details of the invention will appear from 15 the specification and claim.

A preferred embodiment of the invention is illustrated in the accompanying drawing which shows a central section of a working barrel with the standing valve puller in place 20 therein.

1 marks the working barrel, 2 the standing valve seat, 3 the standing valve, 4 the standing valve seating surface, 5 the cup of the standing valve, 6 the standing valve cage, 7 the standing valve seat, 8 the ball operating on the seat, and 9 a screw-threaded opening in the upper end of the cage. These parts are of common construction. A sucker rod 10 has the usual screw-threaded socket 11 at its 25 lower end. A puller shank 12 is provided with a screw-threaded upper end 13 adapted to be screwed into the socket 11. It is provided with a square wrench hold 14 to facilitate screwing it into place.

The lower end of the shank is screw-threaded at 15 and the screw thread is adapted to engage the screw threads of the opening 9. The screw threads are slotted at 16 giving it the effect of a tap so that it may cut its way 40 into the opening 9 even though the ordinary threads therein are quite mutilated.

The shank is formed with a scraping blade 17 preferably in the form of a spiral which is adapted to fit the walls of the working 45 barrel.

In operation the device is lowered into the working barrel and by reciprocating it at this point the working barrel walls may be completely cleaned. Any deposit, or material, there may be in the working barrel can 50 be penetrated by the device so that the lower screw is brought into engagement with the screw-threaded socket of the cap. The scraping blades not only scrape the walls of the working barrel but center the screw so that 55 it can readily enter the cap. Upon lifting the standing valve the fact that the walls of the working barrel are cleared assures the ready withdrawal of the valve through the working barrel, the scraping blades carrying 60 with them some of the material ahead of the valve.

What I claim as new is:—

A barrel cleaning device comprising scrapers 65 adapted to scrape the walls of the working barrel, said device having a screw-threaded lower end adapted to engage a standing valve, the scrapers extending to the upper end of the screw threads, and an upper end adapted to engage an operating rod.

In testimony whereof I have hereunto set my hand.

DANIEL E. NORRIS.
